CHRISTIAN A. CHRISTOFFERSON AND WILLIAM M. MCCLINTOCK, OF ST. PAUL,
MINNESOTA.

BATTERY-WELL.

1,158,894.

Specification of Letters Patent.

Patented Nov. 2, 1915.

Application filed December 8, 1913, Serial No. 805,412. Renewed September 28, 1914. Serial No. 864,001.

To all whom it may concern:

Be it known that we, CHRISTIAN A. CHRISTOFFERSON and WILLIAM M. MCCLINTOCK, citizens of the United States, residents of 5 St. Paul, county of Ramsey, State of Minnesota, have invented certain new and useful Improvements in Battery-Well, of which the following is a specification.

The object of our invention is to provide 10 a battery well of comparatively light construction and easily handled, but at the same time capable of withstanding the lateral pressure to which wells of this type, buried in the ground, are ordinarily subjected.

A further object is to provide a well which will be durable and capable of withstanding the frost and moisture of a cold climate.

The invention consists generally in various 20 constructions and combinations, all as hereinafter described and particularly pointed out in the claims.

In the accompanying drawings forming 25 part of this specification, Figure 1 is a vertical sectional view, through a battery well embodying our invention, taken on the section line substantially of $x-x$ of Fig. 2, Fig. 2 is a sectional view on the line $y-y$ of Fig. 1.

30 In the drawing, 2 represents the outer shell or cylinder of the well. This is formed preferably of a grade of iron that is practically pure, thereby avoiding electrolytic and chemical action and greatly increasing 35 the life of the shell. To increase the strength of this shell and at the same time form dead air spaces, the middle of the shell is provided with a series of annular corrugations extending from the bottom to the

40 top of the well. This shell is inserted into an excavation in the ground. The corrugations are preferably annular or circumferentially arranged in the wall of the shell, and when the well is buried in the ground, 45 the soil will be forced in between the corrugations and becoming packed therein, will resist the upward movement of the shell arising from the action of water or frost. 3 represents a disk, preferably of wood, connect-

50 ed by a series of bars 4 with a similar disk 5 having a central opening 6 therein. These disks and bars form a skeleton frame that is wrapped with a moisture-proof paper or cloth 7, suitably impregnated with a compound that is impervious to moisture. Suit-

able shelving 8 is arranged upon the bars 4 around the skeleton frame, supported by upright rails 9 which surround a central opening 10 in the well.

Between the moisture proof wrapping for 60 the skeleton frame and the outer shell a series of dead air spaces 11 are provided in the corrugations of the shell, which operate as a heat insulating means and also protect the battery cells from frost and cold air. A 65 metal plate 12 is provided beneath the wooden disk 3 and adapted to rest upon the lower corrugations of the metal shell or jacket. The shelving frame is also provided with a third disk 13, spaced a suitable distance 70 from the disk 5 and forming a dead air chamber at the top of the well and insulating the battery cells at that point. This disk 13 has suitable cover sections 14 and the opening 6 in the disk 5 is also provided 75 with a cover 15. Through these openings access may be had to the interior of the cell. The disk 5 has a metal plate 16 at the top and a corrugated neck 17 is mounted on the disk 5 and encircles the opening 6 and projects a suitable distance above the ground 80 line, and is provided with a cover 18. A pipe 19 extends down through the top of the wall to receive a cable for connection with the battery.

In the manufacture of this well, the frame work, wrapped with the heat or cold insulating material, is inserted into the corrugated cylinder and the metallic disk 16 with the neck 17 thereon is then secured in place 90 to the top of the cylinder wall. The joints at the top and bottom of the well are made water-tight by soldering or by suitable cement, or by welding with the oxy-acetylene process. When this has been done, the well 95 is ready to be lowered into the excavation and the batteries connected to the circuit. A well of this type is comparatively light in weight, and but little effort is required to handle it. It is impervious to moisture 100 and is also protected thoroughly by the heat insulating material, while at the top an insulating space is provided between the upper and the adjacent disk.

We claim as our invention:

1. A battery well comprising a metallic shell adapted to be buried in the ground and having a series of annular corrugations formed therein, a frame composed of upright bars, and battery shelves fitting with-

in said shell and having disks at the top and bottom secured to said shell, an insulating wrapping interposed between said bars and said shell, the upper disk having 5 a cover, and a neck encircling said cover to extend above the ground line and through which access may be had to said battery shelves.

2. A battery well comprising a cylindrical outer shell provided with a series of 10 annular corrugations therein, a skeleton battery frame fitting within said shell and having an inner insulating disk at the bottom and an outer metallic disk provided with a 15 water-proof joint with the lower end of said shell, the top of said battery frame having an inner insulating disk and an outer metallic disk also joined to said corrugated shell, said upper disk having an opening therein, 20 a neck encircling said opening and secured to said metallic disk and an insulating wrapping encircling said battery frame between it and said corrugated shell, there being a dead air space between said corrugations and said 25 wrapping.

3. A battery well comprising an outer shell having a series of horizontal corrugations therein and a shelving fitting within 30 said shell and comprising vertical bars and an insulating wrapping therefor, said wrapping being adjacent to said corrugations and forming therewith a dead air space in the walls of said well, said shelving also having 35 disks or heads at the top and bottom of said well, the upper disk having an opening through which access may be had to said well.

4. A battery well comprising a shell adapted to be buried in the ground and having an 40 opening in its top and provided in its walls with a series of annular corrugations, the soil becoming packed between the ribs of said corrugations and resisting the upward movement of said shell, an insulated battery 45 supporting shelving arranged within said shell, and a cover for said top.

5. A battery well comprising a shell adapted to be buried in the ground having

a series of corrugations therein, a battery supporting shelving arranged within said shell, and insulating wrapping interposed between said shell and said shelving, there being dead air spaces formed between said 50 wrapping and the walls of said corrugations.

6. A battery well comprising a shell, 55 adapted to be buried in the ground, and having a series of annular corrugations formed therein, a battery supporting shelving arranged within said shell, a cover for said shell having an opening therein through 60 which access may be had to said shelving, a neck encircling said opening and projecting above the ground line, and a cover for said neck.

7. A battery well comprising an outer shell having a series of horizontal corrugations therein, and a battery supporting shelving fitting within said shell, and an insulating wrapping for said shelving, disks provided at the top and bottom of said shelving, 70 the upper disk having an opening through which access may be had to said shelving and to the interior of said well.

8. A battery well comprising a shell adapted to be buried in the ground and having a 75 series of corrugations therein, a battery-supporting shelving arranged within said shell, a cover for said shell having an opening therein through which access may be had to said shelving, a neck encircling said opening, and a cover for said neck.

9. A battery well comprising a shell adapted to be buried in the ground, a battery-supporting shelving arranged within said shell, an insulating wrapping for said shelving, 85 a disk provided in the top of said shelving and having an opening through which access may be had to said shelving, and a cover for said well.

In witness whereof, we have hereunto set 90 our hands this 22nd day of November, 1913.

CHRISTIAN A. CHRISTOFFERSON.

WILLIAM M. MCCLINTOCK.
